COIN DEVICE

Otto A. Hokanson, Snyder, N. Y., assignor to The
Rudolph Wurlitzer Company, North Tonawanda, N. Y., a corporation of Ohio

Application January 12, 1944, Serial No. 517,962

14 Claims. (Cl. 194—97)

1

This invention relates generally to certain new and useful improvements in coin devices, but more particularly to a multiple coin selector adapted to separate genuine coins from spurious or unacceptable coins and thereby prevent the latter from operating the apparatus to which the selector is attached.

One of its objects is to provide a coin device of this character which has been designed for use with nickels, dimes and quarters, and whereby the introduced coins are automatically directed from a common entrance chute or selector guide to one or the other of two testing chutes and while traveling through such chutes subjected to various tests for separating the acceptable from the unacceptable coins and directing them to different paths of discharge.

Another object of the invention is to provide a novel entrance chute or selector guide for different denomination coins which is displaceable to one or the other of two positions to effectually direct certain denomination coins to one testing chute and wherein it is governed directly by another denomination coin to selectively displace the guide to the other of its positions to present such coin to the other testing chute.

A further object is to provide the coin device with simple and reliable means for simultaneously scavenging both chutes of arrested or trapped unacceptable coins.

A still further object of the invention is to provide the different denomination, acceptable discharge passages with coin-actuated means for registering the passage of an acceptable coin through the device.

Other features of the invention reside in the construction and arrangement of parts herein-after described and particularly pointed out in the appended claims.

In the accompanying drawings:

Figure 1 is a front view of the coin device embodying my invention. Figure 2 is a rear view thereof. Figure 3 is a top plan view of the same. Figure 4 is a sectional elevation of the front side of the device with parts broken away to show the nickel and dime coin testing chute and specifically the path of travel of a genuine nickel. Figure 5 is a similar view, but showing the path of travel of a genuine dime. Figure 6 is a sectional elevation of the rear side of the device with parts broken away to show the quarter testing chute and the path of travel of a genuine quarter. Figures 7 and 8 are vertical sections taken on the correspondingly-numbered lines in Figures 1 and 2. Figures 9 and 10 are horizontal sections taken

2

on the correspondingly numbered lines in Figure 1. Figure 11 is a detached perspective view of the common coin selector guide in its normal position for directing nickels and dimes to their coin-testing chute.

Similar characters of reference indicate corresponding parts throughout the several views.

In its general organization, this device consists of a housing composed of a center plate or partition 10 constituting a supporting frame, and displaceable side plates 11 and 12 hinged in normally spaced parallel relation to the front and rear sides of the center plate and forming and defining therewith upright coin-testing chutes 13 and 14, respectively, extending from side to side of the plates for the downward travel of coins of different denominations; a common coin-introducing means or coin-governed selector guide indicated generally by the numeral 16 disposed at the top and adjacent one side of the housing in correlation with the upper ends of the coin-testing chutes and automatically operative to selectively direct a coin or coins of certain denominations, say nickels and dimes, to one of the testing chutes and coins of another denomination, say quarters, to the other testing chute; means in the respective chutes for testing and defining acceptance and reject paths for the coins and for deflecting and sorting the acceptable from the unacceptable coins of different denominations into predetermined separate paths; means for displacing the chute-forming side plates to release non-acceptable, trapped coins and for scavenging other coins which have been arrested in their travel through the device by failure to meet the requirements or characteristics of genuine or acceptable coins; and slug boxes or receptacles 17 mounted on opposite sides of the lower end of the center plate and into which rejected or scavenged coins are directed. Acceptable nickles and dimes are discharged through openings 18 and 19, respectively, at the lower end of the front side of the center plate 10 in line with the chute 13, while acceptable quarters are discharged through an opening 20 at the lower rear side of the center plate in line with the companion chute 14 after successively passing through such testing chutes. Just prior to passing through their respective discharge openings, the coins encounter switch-closing devices which function to close circuits for registering the passage of acceptable coins through the device.

The center plate 10, which constitutes the supporting frame of the device, is flanged at its opposite side edges, as indicated at 21, and the dis-

placeable side plates 11, 12 are separately hinged on companion upright pintles 22, 23, respectively, mounted on lugs 24 formed at opposite sides of the base plate and inwardly along one of the side flanges thereof. Springs 25 coiled about these pintles and bearing at one end against the corresponding side plates serve to normally retain the latter in their spaced, chute-forming relation with the center plate, and yieldingly resist their outward displacement. The side plates terminate at their lower edges above the lower edge of the center plate and the slug receptacles 17 occupy the space therebelow, their rear walls forming continuations of and being in the same plane as the companion side plates to accordingly provide the lower or final paths of the respective coin chutes 13 and 14 for the discharge of the different denomination coins through the openings 18, 19 or 20. The front or outer walls of the slug receptacles preferably extend some distance above the companion inner walls thereof, as shown, to assure the deflection of tested, unacceptable coins into the receptacles, while their bottom walls preferably converge downwardly and terminate in a common discharge opening 26 through which the rejected coins pass from the device to a reject chute, not shown. Certain rejected coins, say nickels and dimes, may not be deflected into the slug receptacle but instead are adapted to be discharged through an opening 27 formed at the lower end of the testing chute 13 and located at one side of the nickel acceptance discharge opening 18.

The coin-governed selector guide 16 is located at the upper end and at one side of the device for selective registration at its lower end with the upper end of either coin chute, and functions to direct the deposited or introduced coins to one or the other of the chutes 13, 14 for test, the coins rolling edgewise downwardly through the chutes and being subjected to various tests to separate the genuine from the spurious coins and preventing spurious coins or slugs from registering and initiating the operation of the apparatus to which the coin device is connected. Disposed vertically along the outer side of this guide and applied to the adjoining center plate-flange 21 is a coin-engaging reaction plate 28 along which the outer edges of the coins roll while passing through the guide, while disposed above the entry or mouth of this guide and at the opposite or inner side thereof is a gage plate 29 which is adjustably mounted in any well known manner for transverse adjustment on an upward extension of the center plate 10 and which is so spaced relative to the reaction plate to provide a coin-diameter gage opening of a size to receive all coins up to the size of a minted quarter, so that oversized spurious coins are prevented from entering the guide and are immediately trapped above the entrance thereto.

In its preferred construction this coin-governed selector guide consists of a pivoted or pendant trough or funnel-like member including a yoke 30 supported on a horizontal pivot 31 mounted on a bracket 32 suitably fastened to the outer face of the rear side plate 12 adjacent the upper end and at that side thereof remote from its hinged pindle 22. Depending from the inner end of this yoke at one side of its pivot and in correlation with the open upper ends of the chutes 13, 14 are opposing spaced members 33 which converge downwardly and constitute the trough or funnel into which the coins are introduced and from which they are discharged into one or the other of the testing chutes. At its outer end and

on the opposite side of the pivot 31 the yoke is provided with a counterweight 34 which normally tends to swing the yoke downwardly to bring the trough-forming members 33 into communicating relation with the testing chute 13 for directing nickels and dimes thereto. When the yoke is moved in the opposite direction or against the counterweight, then the trough-forming members are accordingly shifted out of register with the chute 13 and into register with the companion chute 14 for directing quarters thereto for test. The trough-forming members are open at their opposite side edges and the resulting funnel-shaped opening for the travel of the coins is transversely in line with the coin-engaging reaction plate 28, so that as the coins are introduced into the selector guide their outer edges engage such plate. Disposed below the pivot 31 and spaced laterally from the reaction plate less than the diameter of the quarter are superposed coin-engaging fingers 35, 36 which extend across the inner edges of the trough-forming members in the edgewise path of travel of quarters but outside the range of travel of nickels and dimes. These fingers are laterally bent from companion vertically swinging levers 37, 38, respectively, which are disposed side by side on the outer face of the bracket 32 and are mounted on corresponding horizontal pivots 39, 40. The levers 37, 38 are latched in their normal coin-engaging positions by a latching lug 41 formed on the lever 38 engaging a companion notch or shoulder 42 formed on the other lever 37. Projecting from the hub of the lever 38 is an arm 43 connected by a link 44 with the outer end of the yoke 30. By this construction, when a quarter is introduced into the selector guide it successively engages the fingers 35 and 36 to first unlatch the levers 37, 38, whereupon the counterweighted yoke is free to rock in a direction to displace the guide to bring its funnel-forming members 33 out of register with the chute 13 and into register with the quarter-testing chute 14. In order to retain the guide in this position for the predetermined time required for the coin to enter the testing chute, I provide a latching lever 45 which is pivoted intermediate its ends at 46 to the lower end of the bracket 32 in cooperative relation at its inner end with a latching lug 47 projecting radially from the hub of the lever 38, whereby the parts are latched in their displaced position. Applied to the other end of this latching lever and disposed in the path of travel of the quarter as it is discharged from the guide into this chute, is a transversely-extending finger or tappet 48 adapted to be tripped by the passing coin to swing and restore the latching lever to its normally released position and permit the counterweighted yoke to return to its normal position and the levers 37, 38 to be again latched in their normal position with the trough-forming members in register with the nickel-dime chute 13. As before stated, the fingers 35, 36 are so spaced from the reaction plate 28 that nickels and likewise dimes do not encounter these fingers and therefore do not disturb the normal position of the guide which is that of directing nickels and dimes to their common testing chute 13.

Disposed in the path of the coins as they travel through the selector guide is a transversely-disposed tappet finger 49 which is applied to the lower end of a vertically-swinging counterweighted bell crank 50 pivoted on the upper outer side of the displaceable side plate 11, the tappet finger projecting through an arcuate slot 51 in such plate. This finger tends to urge the coins

against the reaction plate 28 so that in dropping away from the guide into the testing chute 13, nickels and dimes will drop upon the leading end of a sloping coin-runway 52 mounted on that side of the center plate 10 opposed by the companion displaceable side plate 11. Introduced quarters, after leaving the displaceable selector guide, drop onto a similar sloping runway 53 mounted on the opposite side of the center plate which forms the other testing chute 14. Spanning the testing chute 13 above the runway 52 is a coin diameter gage 54 which is mounted on the displaceable side plate 11 for elevational adjustment relative to the runway and whose inner end has a shouldered element 55 thereon which engages a companion opening 56 in the center plate. This gage is adjustably set for the diameter of a genuine nickel and therefore arrests or traps all coins of larger diameter than a nickel so that they are prevented from passing on through the device. The provision of the shouldered element serves to effect the release of the trapped coin by compelling its lateral movement with the displaceable side plate 11 when the latter is swung open to its scavenging position in the manner to be hereinafter described.

Operatively positioned along the nickel and dime testing chute 13 adjacent the trailing end of the coin-runway 52, and mounted on the front plate 11, is a magnet 57 which sets up a magnetic flux and thereby serves to regulate the speed of travel of the coins, whereby spurious coins, depending upon their conductivity, are retarded more or less so that the path of trajectory of the different coins, after leaving the runway, varies. Disposed adjacent the lower end of the chute 13 and at that side thereof opposing the trailing end of the coin runway therein is an anvil 58 which is secured to the center plate 10 and against which nickel coins are trajectory and from which they are rebounded, if genuine coins, to the nickel discharge opening 18 and if spurious coins, to the reject discharge opening 27. In its rebounded trajectory, a genuine nickel passes between spaced upper and lower studs 59, 60 which extend or bridge the lower portion of the testing chute 13. An arcuate-shaped guide 61 is also positioned in this chute in the trajectory beyond these studs and acts to deflect a genuine nickel downwardly through its acceptance discharge opening 18. A coin of harder metal and of less conductivity than a nickel is less retarded by the magnetic flux and after striking the anvil rebounds along a higher trajectory, striking the upper stud 59 from which it is deflected in a reverse path and downwardly into the reject opening 27. A coin of softer metal and of more conductivity than a nickel is more retarded by the magnetic flux and may or may not reach the anvil. In the event that it does not strike the anvil it will be discharged forthwith through the reject opening. If it does strike the anvil it feebly rebounds therefrom and drops or rolls directly into the reject opening. If the coin does rebound to a greater extent from the anvil it will strike the lower stud 60 and be deflected therefrom in a reverse path into the reject opening.

A dime, after leaving the selector guide 16, enters the same coin testing chute 13 as the nickel and travels down the same runway 52. A genuine dime, which is somewhat retarded by the magnetic flux created by the magnet 57, falls in a substantially straight vertical path after leaving the end of the runway upon a diverter or separator member 62 positioned across the chute sub-

stantially centrally thereof. This diverter is adjustably mounted in any suitable manner on the side plate 11 and is so located that its separating edge 63 is somewhat to the right, viewing Figure 5, of the center of gravity of an intercepted genuine dime. Consequently the dime is deflected to the left by the diverter and is guided to the companion acceptance opening 19 through the medium of the upper convex surface of the arcuate guide 61. In this connection the diverter is pivoted to rock slightly to the right by the impact of the coin to cushion the fall of the same but is prevented from rocking in the opposite direction. A spurious dime of a metal which is more retarded by the magnetic flux leaves the runway in a steeper, vertical trajectory and in so doing encounters an adjustable deflector 64 also mounted on the side plate 11 and extending across the coin chute immediately below the trailing end of the runway 52, such coin being thereupon deflected to the right and encountering the diverter 62 with its center of gravity to the right of the separating point 63. To prevent such coins from dropping and gravitating further in the coin chute and encountering the nickel-engaging anvil 58, the diverter is sloped in a direction to cause the spurious coin to be deflected laterally or outwardly through an opening 65 formed between the opposing edges of the side plate 11 and coplanar rear wall of the companion slug receptacle 17. A spurious dime of a metal which is less retarded than a genuine dime follows a greater trajectory and drops onto the right side of the diverter and is deflected into the slug receptacle in the same manner as the spurious coin just described.

Referring now to the means for testing quarters and spurious coins of like denomination, after leaving the selector guide 16 they drop onto the runway 53 and adjacent the trailing end of the latter is a magnet 66 which is mounted on the side plate 12 in opposing relation to the magnet 57 and which serves to regulate the speed of travel of such coins. A genuine quarter, after leaving the runway, travels in a downward trajectory where it encounters, to the right of its center of gravity, a yieldably counterweighted deflector 67 adjustably mounted on the side plate 12 and positioned across the chute 14, whereby such coin is deflected to the left and directed downwardly by an arcuate guide 68 positioned in the chute to the acceptance discharge opening 20. A spurious coin, which is less retarded by the magnetic flux, strikes a deflector 69 adjustably mounted on the plate 12 in spaced relation to the end of the runway and from which it is rebounded in a reverse trajectory where it encounters a sloping lip or deflector 70 bent inwardly from a slotted opening 71 formed in the side plate 12 adjoining the companion slug receptacle of and by which lip the coin is directed into such receptacle. A spurious coin which is more retarded by the magnetic flux drops upon the deflector 67 with its center of gravity to the right thereof, from which point the coin is directed upon the sloping lip 70 into the slug receptacle.

The center plate 10 and the displaceable side plates 11, 12 are made of a diamagnetic material, and means are provided for effecting the lateral separation of the side plates from the center plate when it is desired to release any non-acceptable trapped coins lodged in the coin chutes 13, 14, and other means are provided for sweeping any paramagnetic coins or like matter which have been trapped and arrested in their travel 75 through the device by the magnets 57 and 66. For

this purpose, each side plate is provided at its upper end with a roller 72 and operatively disposed above the upper edges of these plates for depressible movement therebetween is a vertically-swinging manually-actuated lever 73 pivoted at 74 to the center plate and having a transverse tappet lug 75 thereon adjacent its free end whose opposite edges 76 converge downwardly and are adapted to contact the plate-bearing rollers 72 in wedge-like fashion when the lever is depressed to cause the side plates to be swung away from the center plate. A spring 77 tends normally to urge the lever 73 to its upper released position. At its free end this lever has a finger-engaging pad 78 thereon and below this pad and projecting from opposite sides of the lever are tappets 79, which, when the lever is depressed, are adapted to engage companion sweep arms 80, each pivoted at 81 to the inner side of its companion side plate 11 or 12 to swing vertically through the respective coin chutes 13 or 14 and across the faces of the magnets 57, 66, and thereby dislodge any coins or other paramagnetic matter that are arrested by the magnets. A spring 82 connected to each sweep arm normally urges it to its upper position above the plane of the corresponding magnet and clear of the respective testing chute. The parts are so arranged that during the initial depressing stroke of the lever 73 the side plates are first separated and during the final stroke thereof the sweep arms 80 are then actuated. The coins which have been dislodged by this scavenging operation drop by gravity into one or the other of the slug receptacles 17.

Below the discharge end of the selector guide 16 and above the leading end of the coin runway 52, the side plate 11 is provided with an escapement opening 83 through which coins less than the diameter of a genuine dime are adapted to be laterally ejected from the device. The lower edge of this opening is flush with the top edge of the runway and extending across the coin chute 13 and substantially vertically of the opening is a counterweighted, vertically-swinging ejector 84 pivoted at its lower end to the center plate 10 for normally urging coins which encounter it against that side of the chute in which the escapement window is located. Should a coin of less diameter than a dime be inserted in the device, it drops onto the runway, at the same time striking the other side of the ejector 84 which forces the coin outwardly through the opening 83 from which it drops by gravity into the adjoining slug receptacle 17. A hood 85 applied to the front face of the side plate 11 over the escapement opening prevents the ejected coins being thrown beyond the plane of the slug receptacle. In order to insure that the lower edge of the plate-opening 83 is maintained flush with the top surface of the runway 52, the free upright edge of the side plate 11 is provided with a notch 86 whose upper edge rests upon a guide block 87 in the normal closed position of such plate. This guide block is mounted on the adjoining side flange 21 of the center plate 10 and is vertically adjustable through the medium of screw and slot connection 88.

As shown in Figure 6, studs 89 extend across the quarter testing chute 14 in the vicinity of the deflector 69 and sloping lip 70 to prevent wild coins from overleaping these parts. Spaced over this sloping lip and also bent outward from the side plate 12 is a companion overhanging portion 90 which serves to confine the travel of the coins

deflected by the lip into the slug receptacle and prevent their overleaping the edge of such lip.

A deflector 91 is bent outward from the lower portion of the center plate 10 in the area below the coin runway 52 in the chute 13 and above the open end of the companion slug receptacle 17 to deflect any trapped coins, dislodged from the runway or swept from the magnet 57 when the side plate 11 is displaced and the companion sweep arm 80 is actuated, into such receptacle.

Located in the lower ends of the respective coin chutes for actuation by accepted coins before they pass through their acceptance discharge openings 18, 19 or 21 are switch-closing devices 15 for registering the passage of the different denomination coins through the device. Each of these devices consists of a lever 92 pivoted intermediate its ends to the inner wall of one or the other of the slug receptacles 17 to rock in a plane toward and from the same and provided at one end with a roller 93 whose axis is parallel to the path of travel of the coins and which extends through an opening 94 in such receptacle-wall into the path of the companion coin chute and in peripheral contact with the opposing face of the center plate 10. The other end of the lever controls a companion leaf-like switch 95, so that when an accepted coin passes between the lever-roller and the center plate it rocks the lever in a direction to permit the coin to pass on and at the same time close the switch included in any suitable registering circuit. In this connection, the switch-governing lever is made of an insulating material and the surrounding walls of the device made of a like material or plastic.

I claim as my invention:

1. In a coin device, a housing having coin chutes disposed laterally side by side for the travel of different denomination coins and being open at their upper ends to receive such coins, common laterally-displaceable coin-introducing means pendants suspended from the housing in correlation with the open upper ends of said chutes for selective registration therewith and for receiving and automatically directing coins of predetermined denominations to one or the other of said chutes, and coin-governed means operatively connected to said coin-introducing means for releasably latching it in one of its positions.

2. In a coin device, a housing having coin chutes disposed side by side for the travel of different denomination coins and being open at their upper ends to receive such coins, normally latched displaceable means disposed in correlation with the open upper ends of said chutes for receiving and automatically directing coins of different denominations to one or the other of said chutes, said means being in the form of a pendant, substantially trough-like member having its lower discharge end normally in register with one of said chutes to deliver a certain denomination coin or coins thereto and being displaceable when engaged by a coin of another denomination into register with the other of said chutes, and means initiated by such other denomination coin for unlatching said displaceable means and for actuating the same into register with the other of such chutes.

3. In a coin device, a housing having coin chutes disposed laterally side by side for the travel of different denomination coins and being open at their upper ends to receive such coins, and a normally latched coin-governed, laterally-displaceable guide pendants suspended from said housing and disposed in correlation with the open upper

ends of said chutes for introducing coins of different denominations to one or the other of said chutes, latching means for the guide, said guide being pivoted to swing into registering position with one or the other of said chutes and including means for normally urging it into a latched condition in one of such positions, and other means initiated by a certain denomination coin when introduced into the guide for causing the unlatching of the guide and the displacement of the latter to the other of such positions.

4. In a coin device, a housing having coin chutes disposed side by side for the travel of different denomination coins and being open at their upper ends to receive such coins, a coin-governed, displaceable guide disposed in correlation with the open upper ends of said chutes for introducing coins of different denominations to one or the other of said chutes, said guide being pivoted to swing into registering positions with one or the other of said chutes and including means for normally urging it into one of such positions, a certain denomination coin when introduced into the guide causing its displacement to the other of such positions, and coin-governed means operatively connected to said guide for releasably latching it in its last-named displaced position.

5. In a coin device, a housing having coin chutes disposed side by side for the travel of different denomination coins and being open at their upper ends to receive such coins, a coin-governed, displaceable guide disposed in correlation with the open upper ends of said chutes for introducing coins of different denominations to one or the other of said chutes, said guide being pivoted to swing into registering position with one or the other of said chutes and including means for normally urging it into one of such positions, a certain denomination coin when introduced into the guide causing its displacement to the other of such positions, and coin-governed means operatively connected to said guide for releasably latching it in its last-named displaced position, said latching means including a coin-engaging trip for releasing the same when the displacement-causing coin reaches a predetermined position relative to the guide.

6. In a coin device, a housing having coin chutes disposed side by side for the travel of different denomination coins and being open at their upper ends to receive such coins, a coin-governed displaceable guide disposed in correlation with the open upper ends of said chutes for introducing coins of different denominations to one or the other of said chutes, said guide being pivoted to swing into registering position with one or the other of said chutes and including means for normally urging it into one of such positions, means operatively connected to said guide and including a part in the introductory path of and for actuation by a certain denomination coin for causing the displacement of the guide to the other of such positions, and means governed by said coin-actuated part for releasably latching said guide in its last-named position, said latching means including a part in the discharging path of and for actuation by such coin for effecting the unlatching of the guide and its return to normal position.

7. In a coin device, a housing having coin chutes disposed side by side for the travel of different denomination coins and being open at their upper ends to receive such coins, a displaceable guide disposed in correlation with the open upper ends of said chutes for receiving and directing coins

of different denominations to one or the other of said chutes and including means for normally urging it to a position in register with one of the chutes, and a motion-transmitting connection for actuating the guide to a position in register with the other coin chute including a coin-engaging member disposed in the introductory path of a certain denomination coin for initiating the operation of said connection whenever such a coin is introduced into said guide.

8. In a coin device, a housing having coin chutes disposed side by side for the travel of different denomination coins and being open at their upper ends to receive such coins, a displaceable guide disposed in correlation with the open upper ends of said chutes for receiving and directing coins of different denominations to one or the other of such chutes and including means for normally urging it to a position in register with one of the chutes, and coin-initiated, motion-transmitting means operatively connected to said guide for actuating it to a position in register with the other coin chute when a coin of a certain denomination is introduced thereto, said means including a part extending into the entry portion of the guide for actuation by such last-named coin.

9. In a coin device, a housing having coin chutes disposed side by side for the travel of different denomination coins and being open at their upper ends to receive such coins, a displaceable guide disposed in correlation with the open upper ends of said chutes for receiving and directing coins of different denominations to one or the other of such chutes and including means for normally urging it to a position in register with one of the chutes, coin-initiated, motion-transmitting means operatively connected to said guide for actuating it to a position in register with the other coin chute when a coin of a certain denomination is introduced thereto, said means including a part extending into the entry portion of the guide for actuation by such last-named coin, and a latching element in cooperative relation with said motion-transmitting means for latching the same and its guide in said last-named position during the travel of the coin through said guide, the latching element including a part disposed at the discharge end of the guide for engagement by said certain denomination coin to release the latching element and cause the return of the guide and its motion-transmitting means to their initial position.

10. In a coin device, a housing having coin chutes disposed side by side for the travel of different denomination coins and being open at their upper ends to receive such coins, a displaceable guide disposed in correlation with the open upper ends of said chutes for receiving and directing coins of different denominations to one or the other of such chutes and including means for normally urging it to a position in register with one of the chutes, coin-initiated, motion-transmitting means operatively connected to said guide for actuating it to a position in register with the other coin chute when a coin of a certain denomination is introduced thereto, said means including a part extending into the entry portion of the guide for actuation by such last-named coin, and a latching element in cooperative relation with said motion-transmitting means for releasably retaining the latter and the guide in their normal position, the latching element including a part extending into the entry portion of said guide in substantially coplanar relation with and in advance of the coin-actuated part of the motion-

11

transmitting means for releasing said latching element upon engagement of such certain denomination coin therewith.

11. In a coin device, a support, a pivoted coin-receiving trough mounted thereon to swing to one or another of two positions for directing different denomination coins to different coin paths, means connected to the trough for normally urging it to swing into one of its positions, and a lever pivoted intermediate its ends on said support and having one arm thereof connected to said trough and the other arm extending into the trough for tripping engagement by a certain introduced denomination coin for actuating said lever to swing said trough into the other of its positions.

12. In a coin device, a support, a pivoted coin-receiving trough mounted thereon to swing to one or another of two positions for directing different denomination coins to different coin paths, means connected to the trough for normally urging it to swing into one of its positions, a lever pivoted intermediate its ends on said support and having one arm thereof connected to said trough and the other arm extending into the trough for tripping engagement by a certain introduced denomination coin for actuating said lever to swing said trough into the other of its positions, and a latch pivoted to said support for releasable engagement with said lever for retaining the trough in such other position, said latch having a trip element thereon disposed in the discharging path of the certain denomination coin for causing the tripping of said latch to its released position and the return of the trough to its normal position.

13. In a coin device, a support, a pivoted coin-receiving trough mounted thereon to swing to one or another of two positions for directing different denomination coins to different coin paths, means connected to the trough for normally urging it to swing into one of its positions, a lever pivoted intermediate its ends on said support and having one arm thereof connected to said trough and the other arm extending into the trough for tripping engagement by a certain introduced denomination coin for actuating said lever to swing said trough into the other of its positions, a latch pivoted on said support for releasable engagement with said lever for latching the trough in its normal position, said latch having a trip element

12

thereon disposed in the trough in advance of said coin-engaging lever arm for engagement by such certain denomination coin for causing the tripping of said latch to its released position and the subsequent swinging of the trough to its other position by said lever, and a second latch pivoted to said support for releasable engagement with said lever for retaining the trough in such other position, said latch having a trip element thereon disposed in the discharging path of the certain denomination coin for causing the tripping of said second latch to its released position and the return of the trough to its normal position.

14. In a coin device, a support, a pivoted coin receiving trough mounted thereon for movement to one or the other of two positions for directing different denomination coins to different coin paths and counterweighted to normally urge it to one of such positions, and lever and link means mounted on said support and operatively connected at one end to said trough and provided at its other end with a coin-engaging actuating arm disposed in intersecting edgewise relation to the inlet portion of said trough for initiating the movement of the lever and link means in a direction to swing said trough to the other of its positions whenever a coin of a certain denomination is introduced thereto.

OTTO A. HOKANSON.
